(57) **CLAIM**

The ornamental design for a clip for mounting a microphone, camera or combination of microphone and camera to a garment, as shown and described.

DESCRIPTION

FIG. 1 shows a front perspective view of a clip for mounting a microphone, a camera or a combination of a microphone and a camera to a garment according to my new design; FIG. 2 shows a top plan view of the clip of FIG. 1; FIG. 3 is a side view of the clip of FIG. 1, viewed from the left side of the clip as shown in FIG. 1; FIG. 4 is a front view of the clip of FIG. 1; FIG. 5 is a side view of the clip of FIG. 1, viewed from the right side of the clip as shown in FIG. 1; FIG. 6 shows a bottom plan view of the clip of FIG. 1; FIG. 7 is a back side view of the clip of FIG. 1; and, FIG. 8 is a front perspective view of the clip of FIG. 1, shown in an environment of use with a shirt garment and a camera. Broken lines in FIG. 8 showing a shirt garment and camera illustrate environment and form no part of the claimed design.
